UNITED STATES PATENT OFFICE

JULIUS A. HEINZ, DECEASED, LATE OF PESOTUM, ILLINOIS, BY KATHRYN KERWIN HEINZ, OF PESOTUM, ILLINOIS, AND FRED B. HAMILL, OF CHAMPAIGN, ILLINOIS, EXECUTORS, ASSIGNEES TO HEINZ FLORAL RACK CO., OF CHICAGO, ILLINOIS, A CORPORATION

ARM AND BOTTLE HOLDER

Application filed December 29, 1927. Serial No. 243,422.

This invention relates to an arm and bottle holder for use by undertakers during embalming processes the present invention consisting of various improvements in that for which application No. 211,475 was filed on 5 August 8, 1927, and which matured into Patent 1,671,862, issued May 29, 1928, and it is an object of the invention to provide a simple and inexpensive device of this character, 10 which possesses the necessary rigidity for holding the arms of a body in elevated position for drainage purposes and in a natural position during the injection of the embalming fluid. It is a further object of the invention to provide convenient adjustable and 15 detachable means for supporting the bottle of embalming fluid as well as to provide a detachable drainage or drip pan, all as will be hereinafter more particularly described and 20 claimed.

Referring to the accompanying drawings which are made a part hereof and on which similar reference characters indicate similar parts,

Figure 1 is a perspective illustrating one 25 application of the invention,

Figure 2, a fragmentary detail,

Figure 3, a top plan view of the bottle holding and tube constricting member, and

Figure 4, a top plan view of the drainage 30 or drip pan.

In the drawings reference character 10 indicates a base formed of a substantially flat hollow body or base having arms 11 and 12 35 slidably mounted in its ends, each arm comprising a horizontal portion and a vertical portion disposed at right angles thereto. The horizontal portions of the arms are provided with slots 13 and 14 through which extend bolts or screws 15 and 16 carried by the base 10, said slots and bolts serving to prevent the removal of the adjustable arms from the base. Bolts or screws are preferable to fastening elements which are not removable since 40 they permit the device to be taken apart for cleaning and other purposes.

In order to prevent the base 10 from tilting or falling over when in use, a detachable cross member or support 17 may be provided having a pair of upstanding elements 18 and 19

spaced transversely of the same and adapted to be disposed in either of the slots 13 or 14 in the adjustable arms carried by the base to prevent relative rotation of the respective parts. In order to fasten the parts together 55 the element 19 is preferably threaded to receive a wing nut 20. It will be understood of course from the foregoing that the cross member may be secured to the arms at either end of the base but ordinarily it will be practical and desirable to secure it at the end shown in order to better support the device.

The upright portions of the arms 11 and 12 are provided with studs 21 and bolts 22 disposed in longitudinally spaced relation and which extend through slots 23 in vertically adjustable brackets 24 having curved members 25 pivoted at their upper ends. The brackets 24 and curved members 25 form adjustable arm supporting members. The bolts 70 22 are provided with wing nuts 22' by means of which the brackets may be secured in the desired adjusted position. The members 25 are adapted when in use to be disposed in the position shown but when packed for carrying are adapted to be folded inwardly so that they fit snugly against the opposite sides of the brackets.

A drip or drainage pan 26 is provided such 75 drip pan having a socket 27 on its under surface adapted to fit into the short end of the cross member 17 for holding the pan in operative position.

The device above described is suitable for 80 supporting the arms of a corpse upon a cooling board or other device upon which the same rests either during the embalming of the same or while the corpse is on display. The device is adjustable to the desired width or height obviating the necessity of tying the 85 hands or arms of the body in position either during the embalming operation or after the same is performed and by its use blood may be thoroughly drained from the veins and arteries and discolorations cleared from the 90 finger tips and other parts of the body.

Means is provided for supporting a bottle 95 28 of embalming fluid having a rubber hose or tubing 29 and for pinching the tubing to shut off the flow therethrough. Said bottle 100

supporting bracket comprises a socket 30 having a supporting bracket 31 at its upper end for the reception of a threaded stud 32 upon which the same is held by means of a wing nut 33, the stud 32 being formed integral with the stud 22 if desired. At the lower end of the socket 30 is mounted a supporting bracket 34 provided with a slot 35 for the reception of a threaded stud 36 carried by the vertical part of the arm 11, a wing nut 37 being provided for fastening the bracket 34 in fixed position. It will be understood from the foregoing that the socket 30 is angularly adjustable. The socket 30 is provided with a pin 38, the lower end of the pin 38 being adapted to fit into the lower bifurcated end 39 of a tube 40 provided with a large upper end 41 through which is threaded a set screw 42 the bifurcated lower end of the tube 40 and the pin 38 serving to prevent the tube from turning in the socket 30. A second tube 43 is mounted in the tube 40. The same also has a large upper end 44 through which is inserted a set screw 45. A rod 46 is mounted in the tube 43 and has fixed on its upper end a bottle holding and tube constricting element 47 which comprises a yoke having arms 48 for engaging the neck of a bottle and with a slot 49 between the base of the arms between which the tube 29 may be forced for stopping the flow.

It will be obvious to those skilled in the art that various changes may be made in the device without departing from the spirit of the invention, and therefore, the invention is not limited to what is shown in the drawings and described in the specification, but only as set forth in the appended claims.

Having thus fully described the said invention, what is claimed as new and desired to be secured by Letters Patent, is:

1. An arm and bottle holder comprising a base, a detachable cross member connected to said base for preventing overturning of the base, means for holding the same in fixed transverse position relative to the base, adjustable arm supporting members carried by said base, and a bottle supporting bracket mounted on said base, substantially as set forth.

2. An arm and bottle holder comprising a base, brackets slidable toward and from each other carried by the base, a member for detachable connection at either end of the base for preventing overturning of the same, and adjustable arm supporting members carried by said brackets, substantially as set forth.

3. An arm and bottle holder comprising a base, brackets slidable toward and from each other carried by the base, a member for detachable connection at either end of the base for preventing overturning of the same, adjustable arm supporting members carried by said brackets, and means for supporting a bottle, substantially as set forth.

4. The combination of a base, arm supporting members slidable toward and from each other mounted on the base, a cross member for detachable connection with either of said arm supporting members for preventing overturning of the base, and a bottle support pivoted on said base and adjustable at different angles relative to the base for supporting a bottle in vertical position, substantially as set forth.

5. The combination of a base, arm supporting members slidable toward and from each other mounted on the base, a cross member for detachable connection with either of said arm supporting members for preventing overturning of the base, and a bottle support pivoted on said base and adjustable at different angles relative to the base for supporting a bottle in vertical position, said bottle supporting member comprising a yoke having arms for engaging the neck of a bottle, said yoke having a constricted portion between the arms adapted to constrict the tube for stopping the flow therethrough, substantially as set forth.

6. An arm and bottle holder comprising a base, an arm supporting member at each end of the base, a socket adjustably mounted on one of the arm supporting members, a pin in said socket, a bottle supporting bracket disposed in said socket and having a bifurcation in its end for receiving said pin whereby rotation of the bracket in the socket is prevented, substantially as set forth.

7. An arm and bottle holder comprising a base, an arm supporting member at each end of the base, a socket adjustably mounted on one of the arm supporting members, a pin in said socket, a bottle supporting bracket disposed in said socket and having a bifurcation in its end for receiving said pin whereby rotation of the bracket in the socket is prevented, said bracket comprising a plurality of telescopic sections including rigid pipe sections, substantially as set forth.

8. An arm and bottle holder comprising a base, brackets carried by the brace and adjustable horizontally toward and from each other, vertically adjustable arm supporting members carried by said brackets, a detachable cross member connected to one of the brackets and adjustable therewith toward and from the other bracket, and means for securing said cross member in fixed relation, substantially as set forth.

9. An arm and bottle holder comprising a base, brackets carried by the brace and adjustable horizontally toward and from each other, vertically adjustable arm supporting members carried by said brackets, a detachable cross member connected to one of the brackets and adjustable therewith toward and from the other bracket, means for securing said cross member in fixed relation and means for securing a drainage pan in an op-

erative position adjacent one end of the base, substantially as set forth.

10. An arm and bottle holder comprising a base, brackets carried by the brace and adjustable horizontally toward and from each other, vertically adjustable arm supporting members carried by said brackets, a detachable cross member connected to one of the brackets and adjustable therewith toward and from the other bracket, means for securing said cross member in fixed relation, and an upright bottle supporting member swingable transversely of said base, substantially as set forth.

15. In witness whereof, we have hereunto set our hands at Champaign, Illinois, this 27th day of December, nineteen hundred and twenty-seven.

KATHRYN KERWIN HEINZ,
FRED B. HAMILL,
